UNITED STATES PATENT OFFICE.

FRANK W. MAZSICK, OF NORTH MILWAUKEE, WISCONSIN.

CABINET IRONING BOARD.

Application filed April 5, 1921. Serial No. 458,652.

To all whom it may concern:

Be it known that I, FRANK W. MAZSICK, a citizen of the United States, and resident of North Milwaukee, in the county of Milwaukee and State of Wisconsin, have invented certain new and useful Improvements in Cabinet Ironing Boards; and I do hereby declare that the following is a full, clear, and exact description thereof.

10 My invention refers to built-in ironing-board cabinets of that type, wherein a main board and an auxiliary board are folded within the cabinet when not in use.

15 The primary object of my invention is to provide a simple, economical and effective ironing-board fixture of the above referred-to type, which can be readily fitted into the wall of a building, whereby the maximum of space is obtained with relation to 20 the limitations of wall structures.

Specific objects of my invention are:

25 To provide a rigid and light supporting brace for the foldable ironing-boards, having associated therewith a compensating link mechanism which permits the board or boards to be freely folded, and also performs the function of an elongated supporting shoe for the boards when they are swung to their working positions.

30 To provide an anchor block for supporting the heel of the main board, which anchor block also serves as a means for connecting a single auxiliary ironing-board, it being understood that the auxiliary ironing-board is equipped with a supporting brace similar to the brace associated with the main ironing-board, which brace is pivoted to the anchor board, whereby the parts associated with the auxiliary ironing-board comprise a unit that can be readily fastened to 40 the walls of the cabinet above the main board.

45 With the above and other minor objects in view, the invention consists in certain peculiarities of construction and combination of parts, as are hereinafter set forth with reference to the accompanying drawings and subsequently claimed.

In the drawings:

50 Figure 1 represents a sectional elevation of an ironing-board cabinet embodying the features of my invention, the section being indicated by line 1—1 of Figure 2.

55 Figure 2 is a face view of the same showing the horizontally swinging door of the

cabinet open to expose the parts of the folded main ironing-board, and

Figure 3 is a horizontal section on the line 3—3 of Figure 1.

Referring by characters to the drawings, 60 1—1 represent the board side walls of a box-like cabinet, 2—2 the top and bottom end boards, and 3 the back-board of the structure. As best shown in Figure 1, the wall 3" is reduced in thickness near its lower 65 portion and has secured thereto a sheet metal panel 3'. This panel is substituted for the wooden back-board, so as not to increase the depth of the cabinet, which depth is limited in scope. The apparently slight 70 difference in depth, however, is sufficient to form room or clearance space within the cabinet for storing standard irons or like household implements, it being understood; 75 as best shown in Figure 3, that the cabinet is provided with a horizontally swinging door 4 which is panelled centrally, whereby this space is also slightly increased for the purpose specified.

The cabinet, as shown, is provided with a 80 shelf 5 for the purpose of supporting the irons when placed in the cabinet for storage, it being understood that the shelf is associated with that part of the cabinet wherein the sheet metal panel forms the rear closure 85 thereof, back piece 5' extends from bottom end board 2 to shelf 5, being interrupted between these parts and wall 3".

Secured to the inner face of the back-board 3 is an anchor-board 6, which anchor-board is centrally recessed, as shown at 6' at its upper end, to form legs between which is fitted and pivotally secured the heel end of an auxiliary ironing-board 7.

A skeleton bracket 8 has its lower ends 95 pivotally connected to ears 9 that are secured to the anchor-board, and the upper spaced ends of this bracket or supporting brace 8 are secured to the ends of links, the opposite ends of which links are pivotally connected 100 to ears 11 that are secured to the underface of the auxiliary board. When the auxiliary board is swung outward to its working position, these auxiliary links 10 serve as elongated shoes or supports in connection with the supporting brace 8 for the lower face 105 of the board, which snugly engages said links. Thus the load strain at the outer end of the board is sustained, and due to the somewhat increased surface of the links, a 110

broad bearing will result to prevent sagging.

Directly under the auxiliary board, a main ironing-board 12 is positioned, the heel end of which ironing-board is provided with 5 pivot studs 12' which engage the side boards of the cabinet, the pivot being offset slightly from the outer face of the anchor-board and upon a horizontal plane slightly lower than the bottom edge of said anchor-board, where-
10 by the heel of the main board will engage the lower face of the anchor-board 6 to thus serve as a support for said main board, when it is swung to its working position. The main board 12 is provided with a sup-
15 porting brace 13, having spaced legs which are pivotally secured by pivots 14 to the side boards of the cabinet, and their cor-
responding upper ends are pivotally connected to the free ends of short links 15,
20 which links are in pivotal union with ears 16 that are secured to the lower face of the main ironing-board, this brace construction being similar in all respects to the supporting brace 8 described in connection with the
25 auxiliary board, and obviously functions in the same manner.

As best shown in Figure 2, the spaced legs of the brace 13 are connected by tie straps 13', whereby rigidity of the skeleton struc-
30 ture is assured.

From the foregoing description, it will be readily understood that should the parts

be in their working position, as shown in Figure 1, in order to fold them within the cabinet, the auxiliary board will first be 35 swung back against the back-board of the cabinet and the link 10 will permit such swing by compensating for the different radial motions described, with relation to the supporting brace and swinging board. 40 The main board is swung back into the cabinet in the same manner, and will assume a parallel position beyond the anchor-board and auxiliary board. The irons and other appurtenances can then be placed upon the 45 shelf 5, and the cabinet door, when closed, will thus present a neat appearing structure which is flush with the wall of the building.

I claim:

An ironing board cabinet, an ironing board pivoted to the side walls of said cabinet, a pair of links pivoted to the lower face of said board, a pair of braces pivoted to said links and to the side walls of the cabinet, each of said braces being provided 55 with a strengthening member having its ends rigidly affixed to said brace and bowed inwardly at its intermediate portion, said portions being rigidly connected together.

In testimony that I claim the foregoing I 60 have hereunto set my hand at Milwaukee, in the county of Milwaukee and State of Wisconsin.

FRANK W. MAZSICK.
